Crusher Company, Philadelphia, Pa., a cor-
poration of New York

Application May 30, 1942, Serial No. 445,116

1 Claim. (Cl. 241—86)

1

This invention relates to crushers and particularly to those fracturing pieces of material by impact.

The object of the invention is to combine with a thorough impact reduction a further reduction by a group of several bars on an arc approaching the beater circle to give an additional breakdown of the material.

Other objects of the invention, particularly in the construction and cooperation of the parts and their combination with a final impact plate at the discharge, will appear from the following description taken in connection with the accompanying drawings, in which

Fig. 1 is a vertical sectional view of a crushing apparatus embodying the invention;

Fig. 2 is a horizontal sectional view taken on the line 2—2 of Fig. 1;

Fig. 3 is a rear perspective view of the bar group unit; and

Fig. 4 is a perspective view of the end of the impact block side frame adapted for attachment of the bar group unit. In the crusher shown, the casing 5, 6 is the usual construction having a cover 7 formed at its center with a flanged structure 8 around the entrance opening 9 from the hopper. The material passes at high velocity downward through this opening 9 and radially into the beater circle below.

The rotor comprises the usual shaft 10, disks 11 and stirrup beaters 12. Upper breaker blocks 14 protect the cover and overlap with the main breaker or impact blocks or anvils 15, four of which are shown as mounted on each side in an impact block frame 16 formed by end pieces 17 with the cross tie shafts 18. The middle tie shaft 19 is linked at 19 to the pin 20 of an impact block adjusting screw 21 adjusted by the hollow nut and hand wheel 22 journaled in the bearing 23 of the casing offset 24.

The lower portions of the impact block frame 17 are extended as indicated at 25 to provide anchorages for a cast unit 26 comprising a series of bars 27 joined together at their ends as indicated at 28, these end parts 28 being provided with fastening lugs 29 having bolt holes 30 for the bolts 31 attaching the unit to the lower portions 25 of the impact block frames 16. The bar shape 27 is typical and may be altered to meet varying conditions.

Protective baffle plates 33 are provided on each side and a final central breaker block 36 of inverted V formation is hung on the cross shaft 37, or held by other means.

The material entering at 9 moves squarely into

the path of the beaters and is impacted back and forth between the beaters and the impact blocks 15 on the side of the machine toward which the hammers are moving at the top. Then 5 the fractured pieces from these repeated impacts are driven against the bars 27 of the unit 26, these bars being smaller than the impact blocks 15 and positioned on an arc approaching the beater circle so as further to break down and reduce the larger fractured particles. The beaters 12 and the bars 27 particularly cooperate to fracture to smaller size any oversized pieces delivered from the previous impacts. The spaces 38 between bars 27 are generously large for passing of 10 crushed material and preferably widen out radially so as to avoid any retention or jamming of material between the bars. These bars form a "wash board" effect which accomplishes the final reduction within a very short space, shorter 15 than the space allotted to the initial fracturing by impact.

Preferably the group of bars 27 is mounted on the impact block frame carrying the impact blocks 15 so as to be adjusted therewith, but independent adjustment of the bar group unit 26 may be provided. As indicated in Fig. 3, strengthening webs 40 may be provided at the central portion of the group in the spaces 38. Bar group 27 (Fig. 3) may be perforate or imperforate with corrugations as desired.

In the bar group unit shown, the end portions 28 lie snugly within the extensions 25 of the impact block frame pieces 17 and the rear surfaces of these ends rest against the shoulders 41 of the 35 thickened end portions 42 of the frames, as shown in Figs. 2, 3 and 4.

The fractured material finally discharged from the breaker bars 15, 27 is then projected against the surface of the lower breaker block or "kick-off plate" 36 placed to intercept the material leaving the impact blocks at high speed. This "kick-off plate" 36 protects the foundation from the impact of the discharged material and also utilizes the energy of the discharged particles to effect a 40 final reducing action. This breaker block 36 may be in sections for easy renewal of any one piece as shown. When hung on the cross shaft 37, (or otherwise held) which in turn is anchored to the casing or foundation, it is free to adjust itself to the pressure of the impacting material, or it may be provided with a simple locking lever on the outside of the machine clamped in different adjustments to regulate and maintain the desired angularity of the plate.

55 The machine shown is of the reversible type

generally symmetrical on each side of a vertical plane through the center so that the rotor may be reversed to distribute the wear on the opposite sides of the hammers and to use the wear to sharpen the rear edges of the hammers which will then act as the front edges upon the next reversal. The three stages of reduction are compactly attained within 180° with an ample discharge opening between the bar group unit 26 and the kick-off plate 36. The impact fracture by the beaters and impact blocks 15 puts the material into condition so that the next reduction is attained within the several bars carried by the unit 26 in much less space than that occupied by the initial impact fracture stage. The result is a very effective reduction of the oversize material within a restricted space and with economy in the overall expenditure for maintenance and power, the material being broken into substantially properly sized pieces with a minimum development of fines.

We claim:

In a crusher having a rotor carrying beaters in a casing with an upper entrance opening and a discharge opening opposite and below said entrance opening, the combination with upper breaker surfaces around the entrance opening, of

a series of spaced rectangular impact members extending in an arc from said upper breaker surfaces to the level of the axis of the beater and having their relatively long flat inner surfaces in planes inclined forward at an acute angle with the beater circle and adapted to cooperate with said beaters to fracture the material by impact back and forth between the beaters and said members, an impact block frame carrying said impact blocks and pivoted at its upper end and adjustable to vary the distance of the frame from the beater circle of the rotor around the pivot at said upper end of the frame, and a group of relatively small closely spaced bars following said impact blocks and mounted on said frame and having side surfaces nearly radial to the axis of the beater circle and extending from said impact members in a short arc leaving a following ample discharging opening of larger area than said entrance opening and terminating within 180° of the center of said entrance opening, so that there is extended impact fracture followed by a relatively short screen fracture and said stages of reduction and the discharge are compactly attained within 180°.
